UNITED STATES PATENT OFFICE.

HYMAN LEWIS, OF ROCK ISLAND, ILLINOIS.

Brake-Shoe.

No. 909,431.

Specification of Letters Patent.

Patented Jan. 12, 1909.

Application filed March 2, 1908. Serial No. 418,677.

To all whom it may concern:

Be it known that I, HYMAN LEWIS, a citizen of the United States, residing at Rock Island, in the county of Rock Island and State of Illinois, have invented new and useful improvements in Brake-Shoes, of which the following is a specification.

The object of my invention is to provide a reinforcing back for brake shoes which can be made at low cost from commercial iron and which will make a locking engagement with the cast iron body of the shoe and prevent portions of the body from slipping off the back in the event that the shoe is fractured.

In the accompanying drawings I have shown my invention in several forms embodied in a car shoe and in a driver shoe for the purpose of indicating generally the various ways in which the invention may be embodied.

Referring to the drawings Figure 1 is a top plan view of a car shoe showing the back in full lines and the shoe body in broken lines. Fig. 2 is a side elevation. Fig. 3 is a transverse sectional view on the line 3—3 of Fig. 1. Fig. 4 is a view similar to Fig. 1 of a driver shoe showing the invention embodied therein. Fig. 5 is a view similar to Fig. 2 of the driver shoe shown in Fig. 4. Figs. 6 and 7 are detail plan views showing how the notches may be made in the back strips. Figs. 8 and 9 are transverse sectional views.

Referring first more particularly to the car shoe construction illustrated in Figs. 1-3, 4, 4 designates a pair of metal strips which are arranged side by side and embedded in the shoe at or adjacent to the back thereof to form the reinforcing back. These strips are made, preferably, of commercial iron and they are arranged in parallel relation and are spaced apart to permit the body metal to flow therebetween, as shown in Fig. 3. The strips may be exposed at the back of the shoe between the usual lugs thereon or they may be wholly embedded in the body metal as indicated in Fig. 3.

Heretofore strips, rods or bars have been used as a reinforcement in the back of brake shoes but in practice the body metal does not always weld or become sufficiently connected to these strips or rods or bars to prevent portions of the shoe from slipping off the strips or rods or bars in the event of the shoe being fractured. To overcome this difficulty in a

simple and inexpensive manner I provide the back strip with a plurality of notches in one or both of its side edges spaced apart at intervals throughout its length.

In Figs. 1 and 2 I have shown the strips 60 provided with square cornered notches 5 in their outer side edges. In these figures the notches are shown located in the same relative position in both strips and this is of advantage because the strips are duplicates and the notches can be cut with the same dies and in both strips, or in a greater number, in one operation. These notches may, however, be arranged in staggered position on the two strips if desired and notches can be provided in both side edges of the strip in opposite position, or in staggered position as shown in the strips 8 and 9 of Figs. 6 and 7.

In practice the strips are laid in the mold and the cast iron forming the body 6 of the shoe is then poured into the mold. Inserts 7 of suitable character may also be laid in the mold and the body cast thereon in a familiar manner but, it will be understood, my invention can be applied to a solid cast iron or to a composite shoe with equally satisfactory results.

In Figs. 4 and 5 I have shown the invention embodied in a driver shoe and the strips 10 and 11 exposed on the back thereof. The strip 10 is located between the end lugs 12 of the shoe and the ends of the strip are turned up at 10' to lie against the end lugs. The strip 11 is made to conform to the curvature of the back of the shoe and a portion 11' at 90 each end of the strip 11 is shown turned up to lie against the end lugs 12. The attaching lug 13 is engaged beneath the strips 10 and 11 which secure it to the shoe. In Fig. 4 the notches 14 are curved and provided in 95 staggered position in both side edges of the strips, but they may be arranged in opposite position, as shown in Fig. 6, and they may be made square cornered or otherwise as desired.

The strips 10 and 11 may be made flat like the strips 4 and bent to conform to the curvature of the shoe or I may bend down the outer edge 15 of the strip 10 as shown in Fig. 8, or it may be left flat as shown in Fig. 105 9. The metal may be completely removed from the strips to form notches or it may be bent down as indicated by 16 in Fig. 9.

The strips reinforce and strengthen the shoe in a manner common to devices of this 110

kind heretofore used in brake shoes and as the cast iron of the body fills in the notches in the strips there will be an interlocking engagement between the body and the strips which will prevent an end portion of the shoe slipping off the strips in the event of the shoe fracturing. I prefer to provide the strips with notches throughout their length to obtain thereby a more effective interlocking engagement between the parts and to prevent any portion, large or small, of the shoe from slipping off the strips in the event of fracture.

The notches may be made square cornered, as shown in Figs. 1 and 7, or semi-circular, as shown in Figs. 4 and 6. In each case both side edges of each notch are correspondingly shaped so that the notches will provide for a locking engagement with the body metal in each direction lengthwise of the shoe.

What I claim and desire to secure by Letters Patent is:

1. A reinforcing back for brake shoes comprising a pair of strips arranged side by side and embedded in the body of the shoe at or adjacent to its back, said strips having notches in their side edges and the side edges of each notch being correspondingly shaped to make similar locking engagement with the body of the shoe in both directions lengthwise thereof.

2. A reinforcing back strip for brake shoes having a plurality of notches spaced apart in its side edge throughout its length, the parts of the strip stamped out to form said notches being bent downward to enter the body of the shoe.

HYMAN LEWIS.
